UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Substitute for application Serial No. 292,139, filed April 23, 1919. This application filed July 26, 1924.
Serial No. 728,485.

To all whom it may concern:

Be it known that I, RONALD A. McCANN, a citizen of the United States, residing at Swissvale, in the county of Allegheny and

5 State of Pennsylvania, have invented certain new and useful Improvements in Railway-Traffic-Controlling Apparatus, of which the following is a specification.

10 My invention relates to railway traffic controlling systems, and particularly to systems of the type wherein alternating currents are supplied to the track rails, and the cars or trains are provided with governing apparatus which is controlled by such currents in the rails. More particularly, my invention relates to trackway circuits and apparatus for use in systems of the character set forth.

15 In one system of the type mentioned, it has been proposed to employ the usual track circuit current, that is, the current which energizes the track relays, as one of the currents for controlling the train carried apparatus, and to supply another current (which I will term the "line current") to the rails of each track section in such manner that it flows in the same direction in the two rails. When this is done, it will be seen that when a track section is occupied by a train, if the line current is of sufficient magnitude and of proper phase, and if it is sufficiently unbalanced in the two track rails in the rear of the train it may cause the track relay for such section to become energized, thus causing a false proceed signal in the rear of the train.

20 One object of my invention is the provision of means for immediately opening the circuit for the line current for a track section in the event that such current causes energization of the track relay when the section is occupied, thus preventing a false proceed signal in the rear of the train.

25 Another object of my invention is the provision of means for opening the line circuit for a track section in the event that the signal for the next section in advance sticks in a proceed position while the latter section is occupied by a car or train.

30 I will describe one form of trackway circuits and apparatus embodying my invention, and will then point out the novel features thereof in claims.

The accompanying drawing is a diagrammatic view showing one form of trackway circuits and apparatus embodying my invention.

35 Referring to the drawing, the reference characters 2, 2^a designate the two track rails of a railway along which traffic normally moves in the direction indicated by the arrow. The rails are divided, by insulated joints 3, into a plurality of sections or blocks, of which one complete section C—D is shown in the drawing except that the 40 apparatus for section C—D the sole function of which is to control traffic signals and indications in the section to the left of point C is omitted to simplify the drawing, such a full understanding of the invention described herein. It is understood, however, that a complete system embodying my invention will usually comprise a plurality of successive sections each of which is 45 equipped with apparatus similar to that 50 shown in section C—D.

55 Located adjacent the entrance end of section C—D is a roadside signal S^c of the semaphore type, which signal indicates "stop", "caution" or "proceed" according as 60 the semaphore is in the horizontal, inclined or vertical position. A similar signal S^d is provided for the section immediately to the 65 right of section C—D.

70 The section C—D is provided with a track circuit comprising a source of alternating

75 current (transformer T) and a winding 4 of a polyphase relay H, the source and the relay winding being connected across the 80 track rails at the exit and entrance ends of

85 the section, respectively. A reactance 70 is interposed between transformer T and one rail of the section. Relay H comprises the 90 winding 4, which I will term the "track winding", a second or "local winding" 5, a 95 rotor 6 responsive to currents displaced in phase in the two windings, and contacts 7, 8, 34 and 9 operated by the rotor. The local winding 5 is supplied, as hereinafter explained, with alternating current of the same 100 frequency as that supplied to the primary of transformer T, but displaced in phase from the current in winding 4 by substantially 90°.

105 Signal S^c is provided with a caution circuit and a proceed circuit. The caution cir-

cuit is from one terminal B of a suitable source of current through contact 8 of relay H, wire 18, and the operating mechanism of signal S^c to the other terminal O of the same source of current. It will be seen that this circuit is closed only when relay H is energized. The proceed circuit for signal S^c is from terminal B' (at signal S^p) through contact 15 of track relay H^p for the section 10 to the right of section C—D, wire 16, contact 34 of relay H, wire 17, and mechanism of signal S^c to terminal O. It will be seen that this circuit is closed only when relays H and H^p are both energized.

15 The stator winding 5 of relay H is provided with a circuit which passes from one terminal B² of a suitable source of alternating current of the same frequency as that supplied to transformer T, through contact 20 7 of relay H, wires 10 and 11, and winding 5 to the other terminal O² of the same source of alternating current. This winding is provided with a second circuit which passes from terminal B³ of the same source of alternating current through a contact 13 operated by signal S^c and closed only when the signal is at stop, wires 14 and 11, winding 5 to terminal O². Winding 5 is energized, then, when relay H is open, provided that 30 signal S^c is at stop.

18 The actual sources from which current is supplied to signal S^c and winding 5 of relay H are omitted from the drawing in order to simplify the same as far as possible, the terminals of these sources being represented by the letters B, B', etc., and O, O². It is understood, however, that in some instances one source only may be employed, in which cases the points B, B', B² and B³ will 40 all be connected with one terminal of the source, and points O and O² will be connected with the other terminal of such source.

45 The operation of the apparatus, in so far as the control of signal S^c is concerned, is as follows:

When the track section C—D and the section next to the right are unoccupied, relays H and H^p are both energized, so that signal S^c indicates proceed. If then a car 50 or train enters section C—D, it causes relay H to become de-energized, thereby opening the control circuits for signal S^c at contacts 8 and 34, so that this signal moves to the stop position. Relay winding 5 becomes de-energized by the opening of relay contact 7, but as soon as signal S^c moves to the stop position, this winding becomes energized again by virtue of the circuit passing through contact 13. As soon as the entire 60 car or train has passed out of section C—D, track relay H becomes energized, thereby closing the caution circuit for signal S^c, so that this signal moves to the caution position. Contact 13 opens as soon as the signal 65 leaves the stop position, but this has no ef-

fect on winding 5 because the circuit including contact 7 is now closed. When the entire car or train has passed out of the section to the right of section C—D, relay H^p closes, whereupon signal S^c moves to 70 the proceed position.

The trackway apparatus shown herein includes means for causing an alternating line current to flow along the two track rails of the section C—D in the same direction, 75 which current is controlled by traffic conditions in advance. This current is supplied by a transformer U, and its relative polarity is governed by a pole changer P which is operated by signal S^p and is reversed while 80 this signal is between stop and caution positions. When signal S^p is in the proceed or caution position, the path of the line current is from transformer U, through pole changer P, wire 19, contact 25, operated by signal S^p, 85 wire 20, contact 21 of relay H^p, wire 22 to the middle point of an impedance 27, thence through the two track rails 2 and 2^a in multiple to a second impedance 28, from the middle point of which the current flows 90 through wires 31 and 33, back contact 9 of relay H, wires 32 and 24, and pole changer P to transformer U. The current thus supplied is of what I will term "normal" relative polarity. When, however, signal S^p is 95

in the stop position, contact 25 is reversed, so that wire 19 is disconnected from wire 20 and is connected with a wire 23 which leads to the middle point of an impedance 36; the line current is then supplied to the 100 track rails between impedances 36 and 28 only, and owing to the fact that pole changer P is then reversed, the current is then of "reverse" relative polarity. It will be seen, then, that one or the other of the 105 circuits just traced will be closed when a train enters section C—D, provided that relay H opens. In the event that this relay should stick in the closed position due to a mechanical defect, however, it is desirable 110 that line current be supplied to the rails to avoid stopping the train; to do this, I provide the circuit for the line current with a branch around relay contact 9, which branch is from wire 31, through wire 30, 115 signal operated contact 12, and wire 29 to wire 24. Contact 12 is closed when signal S^c indicates proceed and caution, but open when the signal indicates stop. By virtue of this branch, the line circuit is closed when signal S^c indicates proceed or caution, even 120 though relay contact 9 is open.

Before proceeding further, it should be pointed out that the trackway apparatus here shown is intended for co-operation with train carried governing apparatus in the following manner: When the train is on a portion of track which is supplied with track circuit current and also with line current of normal relative polarity, the governing ap- 130

paratus permits the train to travel at high speed, such as 65 miles per hour. When the track is supplied with track circuit current and with line current of reverse polarity, the 5 governing apparatus prevents the train from proceeding at a speed higher than an intermediate value, such as 35 miles per hour. But when the train enters a portion of track from which the supply of either track circuit current or line current has been discontinued, the governing apparatus prevents the train from proceeding at more than a low speed, such as 15 miles per hour. One 10 form of governing apparatus which will 15 operate in this manner with the trackway apparatus shown herein, is illustrated and described in Letters Patent of the United States No. 1,351,991, granted on the 7th day of September, 1920, to Lloyd V. Lewis, for 20 railway traffic controlling apparatus.

Assuming now that section C—D is occupied by a car or train, it is conceivable that owing to a difference in the resistances of the two lines of track rails the line current 25 in the rear of the train may be sufficiently unbalanced in the two rails to cause track relay H to become energized, it being remembered that winding 5 is energized through contact 13 because signal S^c is at 30 stop. If this happens, the relay will open at contact 9 the circuit for the line current, and since contact 12 is already open because the signal S^c is at stop, relay H will immediately become de-energized. If relay H is 35 again energized by line current, the operation will be repeated. Signal S^c can not move more than a few degrees away from the stop position, however, because of contact 13. That is, if relay H remains closed 40 long enough to cause signal S^c to move, or if this signal should move due to the intermittent closure of the relay, contact 13 will open and so will prevent further energization of relay H until this contact again 45 closes. The car or train which is in section C—D is intermittently deprived of line current, and so it may be compelled to proceed at a low speed, but it is protected by a stop signal in its rear. As soon as the entire car 50 or train passes out of section C—D, track circuit current is again supplied to winding 4 of relay H so that this relay becomes energized and so causes signal S^c to move to the caution position. The circuit for winding 5 55 which includes contact 13 becomes opened as soon as the signal leaves the stop position, but the other circuit for this winding is then closed at contact 7, so that relay H continues to be energized.

60 It will be noted that the circuit for the line current is normally closed when signal S^c indicates caution or proceed, but that this circuit is opened in the event that track relay H becomes energized by line current 65 while the section C—D is occupied by a car

or train, provided that signal S^c is at the stop position.

It should also be observed that when a train enters section C—D, the track relay H will be de-energized regardless of unbalance 70 of the line current in the track rails, because the train then forms a shunt directly across the terminals of winding 4 of this relay.

I will now assume that a train enters section C—D, thus opening relay H, and that winding 4 of this relay becomes energized by line current before signal S^c reaches the stop 75 position. Relay H will not become energized to close its front contacts until signal S^c reaches its stop position because winding 5 is de-energized until that time. It follows, 80 then, that contact 12 must be opened before relay H can become energized due to line current, so that it is impossible for the relay 85 to be held energized with the signal in caution or proceed position due to the flow of line current through contact 12.

It will be noted that the circuit for the line current, when signal S^p is in the proceed or 90 caution position, passes through contact 21 of relay H^p. The reason for this is as follows: Signal S^p is, of course, controlled by relay H^p, and is supposed to move to the stop position when relay H^p opens. But if 95 this signal should stick in the proceed or caution position when a train enters the section to the right of C—D, then (neglecting contact 21 for the moment), line current would still be supplied to the rails of section C—D throughout the entire section, instead of to only that portion of the section between impedances 36 and 28 as should be the case. But with contact 21 inserted between wires 20 and 22, it will be seen that if 100 signal S^p should stick at caution or proceed when relay H^p opens, the line circuit will be opened at contact 21 and so section C—D 105 will be deprived completely of line current.

The present application is for the same invention as an earlier application filed by me on the 23rd day of April, 1919, Serial No. 292139, for railway traffic controlling apparatus.

Although I have herein shown and described only one form of trackway apparatus and circuits embodying my invention, it is understood that various changes and modifications may be made therein within the scope of the appended claims without departing from the spirit and scope of my invention.

Having thus described my invention, what I claim is:

1. In combination, a section of railway track, a track relay having a track winding and a local winding, a track circuit including said track winding and a source of current both of which are connected across the rails of said section, a signal for said sec- 125

tion controlled by said track relay, a circuit for the local winding of said track relay including a front contact of the relay, a branch for said local winding circuit around said relay contact and including a contact which is closed or open according as said signal indicates stop or proceed, and a line circuit including the two rails of said section in multiple and having two branches one of which is closed or open according as said signal indicates proceed or stop and the other of which is closed or open according as said relay is de-energized or energized.

2. In combination, a section of railway track, a track relay having a track winding and a local winding, a track circuit including said track winding and a source of current both of which are connected across the rails of said section, a signal for said section controlled by said track relay, means for supplying current to the local winding of said track relay when the signal indicates stop and for subsequently continuing the energization of said local winding when the relay is energized irrespective of the indication given by the signal, and a line circuit including the two rails of said section in multiple and having two branches one of which is closed or open according as said signal indicates proceed or stop and the other of which is closed or open according as said relay is de-energized or energized.

3. In combination, a section of railway track, a track relay having a track winding and a local winding, a track circuit including said track winding and a source of current both of which are connected across the rails of said section, a signal for said section controlled by said track relay, means for supplying current to the local winding of said track relay when the signal indicates stop and for subsequently continuing the energization of said local winding when the relay is energized irrespective of the indication given by the signal, and a line circuit including the two rails of said section in multiple and controlled by a back contact of said track relay.

4. In combination, two successive sections of railway track, a track circuit for each section including a track relay, and a line cir-

cuit including the two rails of the rear section in multiple and a front contact of the track relay for the advance section.

5. In combination, two successive sections of railway track, a track circuit for each section including a track relay, a signal for the advance section controlled by the track relay for such section, and a line circuit including the two rails of the rear section in multiple, said latter circuit being controlled by the track relay and by the signal for the advance section so that when said signal indicates proceed the circuit is closed only if the track relay is energized. 65

6. In combination, two successive sections of railway track, a track circuit for each section including a track relay, a signal for the advance section controlled by the track relay for such section, and a line circuit including the two rails of the rear section in multiple, said latter circuit being controlled by a front contact of the track relay for the advance section and by a contact operated by said signal and closed only when the signal gives 75 a proceed indication.

7. In combination, a section of railway track provided with a track relay having a track winding and a local winding, a line circuit for said section controlled by a back 80 contact of said track relay, and a circuit for said local winding controlled by a front contact of said track relay.

8. In combination, a section of railway track provided with a track relay having a track winding and a local winding, a signal controlled by said relay, means for controlling said local winding by said signal and by said relay, and a line circuit for said section controlled by a back contact of said 90 relay.

9. In combination, a section of railway track provided with a track relay, a signal controlled by said track relay, a line circuit for said section, and means including only 95 said track relay and a circuit controller operated by said signal for detecting false energization of said track relay by line circuit current.

In testimony whereof I affix my signature. 100

RONALD A. McCANN.
